UNITED STATES PATENT OFFICE.

WILLIAM O. HORN, OF NEW YORK, N. Y.

NECKWEAR-RETAINER.

SPECIFICATION forming part of Letters Patent No. 658,177, dated September 18, 1900.

Application filed May 21, 1900. Serial No. 17,329. (No model.)

To all whom it may concern:

Be it known that I, WILLIAM O. HORN, a citizen of the United States, residing in the city, county, and State of New York, have 5 invented a new and useful Improvement in Neckwear-Retainers, which improvement is fully set forth in the following specification and accompanying drawings.

My invention consists of a neckwear-retainer formed of a bar with lips or bills connected therewith, said bills being so disposed that they may engage the lower edge of a collar and so prevent the article of neckwear from rising or upward displacement, and they 10 are elastic, so that the bow, tie, or other article of neckwear may be held close to the collar and avoiding exposure of the collar-button, the retainer also remaining true on the collar, the construction of the bills, further- 15 20 25 30 35

secured to the proper part of the tie so that the bills B are exposed and project upwardly, the bar A in the present case serving to stiffen 55 the band of the tie back of the bow or knot portion thereof. The tie is then adjusted on the collar and the bills are fitted under the lower edge of the neckband of the collar, whereby the front of the tie or the band thereof, if the retainer is applied to either, (or it may be to both,) is prevented from riding upwardly or bearing irregularly on the edge of the collar, and thus the tie preserves its proper position. The bills are, furthermore, elastic 65 or resilient on the bar and so permit the tie to be held close to the collar and cover and conceal the collar-button. It will also be noticed that the limbs C and D, which are continuous of each other and of the bills, are 70 on opposite sides of the bar A and the bends E and F embrace the walls of the slots A' and the lower edge of the bar, and thus strengthen or reinforce the bar, permitting the latter to be made of light and pliable material, such as pasteboard, cardboard, &c. 75 Owing to the openings A' the limbs C and D are prevented from lateral shifting, and so the bills are controlled in their set or adjusted position on the bar. Again, the bills and limbs may be formed of small pieces of metal 80 separate from the bar, so that the size of the latter may be vastly reduced, the saving of which is apparent.

Having thus described my invention, what 85 I claim as new, and desire to secure by Letters Patent, is—

A neckwear-retainer formed of a bar of light and pliable material with an opening therein, and a separate attaching device 90 thereon consisting of a downwardly-extending doubled shank, and an upwardly-extending bill, the latter being continuous of one of the limbs of said shank, the limbs of the shank embracing said bar, the top bend of the limbs 95 of the shank resting downwardly on the top wall of said opening and the bottom bend of the bill resting upwardly against the bottom of said bar.

WILLIAM O. HORN.
